SAFETY DEVICE FOR FIREARMS

Lloyd P. Gaugler, Elysburg, Pa.

Application January 7, 1947, Serial No. 720,511

1 Claim. (Cl. 42—70)

1

This invention relates to a safety device for firearms. It is primarily adapted for sporting guns to prevent the actuation of the ejecting and loading mechanism and also to prevent the trigger from actuating the firing mechanism for guarding against inadvertent firing or discharge of the gun.

It is common in sporting guns, such as shot-guns and rifles, to provide a safety mechanism for preventing the actuation of the loading and ejecting mechanism and also to prevent inadvertent operation of the trigger. In most of these prior devices the finger piece for operating the locking mechanism is arranged on the side of the frame of the gun. For this reason the gun which is provided with the finger piece on the right hand side of the gun may be operated by a person who shoots right-handed but extremely awkward for a left-handed user. Furthermore, the finger piece on the side of the gun is more apt to be inadvertently operated to the off position while the gun is being carried, particularly when the person is going through brush or high weeds. Furthermore, when the safety finger piece is located on the side of the gun, it is located in a position which makes a separate movement of the finger necessary to condition the gun for quick shooting. The present invention is directed to the provision of a mechanism for operating the safety mechanism of a gun which will be located in such a position that it can be readily operated by persons who shoot either right-handed or left-handed. Furthermore, by this invention the finger piece for the safety mechanism is located in what might be termed a natural position on the top of the frame where the finger piece may be operated by the thumb almost automatically as the gun is raised to the user's shoulder.

Accordingly one of the primary objects of the invention is to provide a safety locking mechanism for firearms which might be readily operated by either the right or left shoulder.

Another object is to provide such a safety locking mechanism in a position on the gun frame where it will be less liable to inadvertent operation.

Another object is to provide a safety locking mechanism which must be operated in a direction to unlock the locking mechanism such that when the gun is normally carried and the safety mechanism is struck by brush or weeds there will be a tendency for the safety mechanism to be pushed to the locking position.

Other and further objects will become readily

apparent from the following description when considered in connection with the accompanying drawings, illustrating an embodiment of the invention, and in which:

5. Figure 1 is a partial elevational assembly of all of the gun except the stock and the end of the barrel, with part of the forward part of the stock and the frame broken away to show the operating mechanism;

10. Figure 2 is an enlarged view of Figure 1 with all of the stock removed and with part of the gun frame cut away to show the details of the operating mechanism; and

15. Figure 3 is a partial exploded perspective view showing the trigger mechanism and the safety locking means provided in accordance with the present invention.

The particular type of firearm chosen for the purposes of illustrating the present invention is 20 a heavy caliber rifle including a frame 10, a barrel 11 and a stock 12, extending rearwardly from the tang 13 of the frame. Integral with underside of the frame 10 is a boss 14 to which a lever 15 is pivotally connected at 16 for operating the 25 loading and ejecting mechanism indicated generally by the reference numeral 18. The boss 14, together with the lever 15 serves as the guard for the trigger 17 which is suitably pivoted in the frame at 17a. The firing mechanism includes a 30 firing pin cocking mechanism 19 which is cocked in a firing position when the loading mechanism is closed as will be more readily apparent hereinafter.

The lever 15 is provided with an extension 15a, 35 the end of which is operably associated through a conventional mechanism 21 with the loading and ejecting mechanism 18. The operable connection 21 is conventional and no further description is necessary except to state that its 40 construction is such as to operate the loading and ejecting mechanism back and forth longitudinally of the gun when the lever 15 is operated about its pivot 16. As the loading and ejecting mechanism 18 is pushed home by the operating lever 15, the firing pin cocking mechanism 19 is stopped in the cocked position, shown in Figure 2, when the depending boss 19a engages the firing pin tripping mechanism 22. This latter mechanism includes a link 23, the forward end 45 of which is pivoted to the gun frame at 24 and the other end of which is provided with a transverse pin 25 which engages a slot 17b in an arm 17c on the trigger 17. An integral lug 23a extending upwardly from the link 23 is adapted to 50 engage the depending boss 19a of the firing pin 55

cocking mechanism when the link 23 is normally biased to its uppermost position by means of the U-shaped spring 26. It will be readily apparent from the drawings that during normal operation the gun can be fired by pulling the trigger 17 which will lower the rearward end of the link 23 and with it the integral lug 23a releasing the firing pin mechanism 19 and permitting it to strike the cartridge.

In order that the gun can not be inadvertently discharged, safety locking mechanism is provided for preventing the operation of the trigger 17 or the actuation of the lever 16. To this end a safety catch 27 is adapted to slide in a rectangular channel 28. The safety catch 27 is 15 provided with a depending hook 29 open on the forward side and adapted to engage a transverse boss 31 on the lever 15 when the latter is in the closed position and when the catch 27 is in its forwardmost position. At the same time a forward extension 32 of the catch 27 is adapted to overlie a rearwardly extending boss 33 on the trigger 17. It will be readily apparent that when the catch is in its forwardmost position neither the trigger 17 nor the lever 15 can be operated.

In order that this safety catch locking mechanism may be readily operated by the thumb of the person using the gun, suitable mechanism on top of the tang 13 is provided for operating the catch 27. To this end, a lever 34 is pivotally supported at 36 in a bracket 37 having an integral foot 38 attached to the frame 10 by suitable screws or in any other desired manner. The lower end of the lever 34 is adapted to engage a notch 27b in the upper side of the catch 27. The upper end of the lever 34 is provided with a longitudinal slot 34a which serves as the pivotal connection with a suitable finger piece 39 which is adapted to slide upon the curved upper surface of the rearward end of the tang 13. The finger piece 39 is provided with suitably spaced ears 41 which are apertured to receive transverse pin 42 which is adapted to extend through the holes in the ears and through the slot 34a of the lever 34. The size of the pin 42 and the transverse dimension of the slot is such that there will be substantially no transverse relative motion between the finger piece 39 and the lever 34 but will permit relative longitudinal movement between the ears 41 and the lever 34. It will be readily apparent that since the radius of curvature of the tang 13 is greater than the distance between the upper surface of the tang and the pivot point 36 relative longitudinal movement between the finger piece 39 and the lever 34 is necessary. In order to hold the finger piece 39 against the top of the tang 13 and provide the necessary friction so that the safety mechanism will not operate too easily, a suitable leaf spring 43 having bifurcations 43a

adapted to straddle the outside of the ears 41 is fixed to the underside of the tang 13 by means of a screw 44. The pin 42 referred to above is long enough so that it projects outwardly beyond the ears 41 and the ends thereof are engaged by the bifurcations 43a of the spring 43 which resiliently urges the finger piece 39 against the upper surface of the tang 13.

It will be readily apparent from the above description that the present invention provides a simple safety locking mechanism which is not liable to become inadvertently operated and which may be readily operated by a right-handed or left-handed person.

Although the invention has been described in considerable detail, it will be apparent to those skilled in the art that many variations are possible without departing from the inventive concept, except as limited by the appended claim.

Having thus described my invention, what is claimed is:

In combination in a gun, a frame having a rearwardly extending tang, a shell loading and ejecting mechanism, a firing mechanism, means 25 for locking said mechanisms against inadvertent operation, means for actuating said locking means comprising a bracket carried by said frame, a lever pivoted to said bracket intermediate the ends of said lever and adapted to operatively engage said locking means, the upper end 30 of said lever having a longitudinal slot, a finger piece adapted to slide upon the upper surface of said tang, said finger piece provided with laterally spaced depending ears having transversely aligned holes, a pin engaging said slot in said lever and said holes in said ears and extending outwardly beyond said ears, the diameter of said pin relative to the width of said slot being such that there is no lost motion transversely of the 35 axis of said lever during relative movement of the finger piece longitudinally of the axis of said lever, and a spring on the underside of said tang, said spring having bifurcated ends adapted to straddle said ears and to engage said pin to 40 resiliently urge said finger piece against the upper side of said tang.

LLOYD P. GAUGLER.
